UNITED STATES PATENT OFFICE.

ROBERT E. MITTON AND WAYNE M. BRALEY, OF SALT LAKE CITY, UTAH, ASSIGNEES,
BY DIRECT AND MESNE ASSIGNMENTS, TO MITTON-BRALEY AERO-PLANE CONTROL
CO., OF SALT LAKE CITY, UTAH, A CORPORATION OF UTAH.

CONTROLLING MECHANISM FOR FLYING MACHINES.

1,422,288.

Specification of Letters Patent. Patented July 11, 1922.

Application filed February 4, 1920, Serial No. 356,213. Renewed May 15, 1922. Serial No. 561,168.

To all whom it may concern:

Be it known that we, ROBERT E. MITTON and WAYNE M. BRALEY, citizens of the United States, residing at Salt Lake City, 5 in the county of Salt Lake and State of Utah, have invented certain new and useful Improvements in Controlling Mechanism for Flying Machines, of which the following is a specification.

10 This invention relates to certain new and useful improvements in controlling mechanism for flying machines, which consists of the novel arrangement of parts to be hereinafter described and claimed.

15 One object of the invention is to provide a control which will automatically maintain the lateral and longitudinal stability of flying machines.

Another object of the invention is to provide 20 a control which will instantly guide the machine in any direction, in a modified manner, but when desirable, will make any correction necessary to maintain stability, unaided by the pilot.

25 Another object of the invention is to provide a control with which it would be difficult to place the flying machine far from its natural flying attitude, and thus do away with hazardous "stunts".

30 Other objects and advantages will appear in the following specifications.

Referring to the drawings:

Figure 1 is a front view of an areoplane, showing the invention in place, with the 35 wires attached thereto.

Fig. 2 is a side view of Fig. 1.

Fig. 3 is a plan view of Fig. 1.

Fig. 4 is an enlarged view of the support, pilot's seat, counter-balance and oil plunger.

40 Fig. 5 is an enlarged view of the foot lever for operating the rudder.

Fig. 6 is a side view of Fig. 5.

Similar letters and numerals refer to like parts throughout the several views of the 45 drawings.

A denotes the frame of an aeroplane, B the fuselage, C the right top aileron, C' the left top aileron, D the right bottom aileron, D' the left bottom aileron, E the elevators, 50 F the rudder, I the base or support for the pivot upon which the seat is mounted, G the seat, 2 the pivot, 5 the counter balance. The base 1 is placed in the bottom of the fuselage B and secured thereto. At the

apex of the base 1 is located the pivot 2. 55 We have shown a ball and socket pivot in the drawings, but we do not bind ourselves to use any certain pivot, we may use any other design. Through the ball 2' of the ball and socket pivot, runs the rod 4 to the 60 upper end of which is secured the pilot's seat G while the counter balance 5 is mounted at the lower end of said rod. The counter balance 5 is so mounted on the rod 4 that it can revolve and be adjusted to any 65 desired location on said rod so that it may counter balance the pilot's body.

Secured to the pilot's seat G is a connecting rod of an oil plunger 35 said connecting rod may have a universal joint (not shown). 70 The oil plunger being secured to any desired part of the frame by suitable means.

Control wires 6 and 6' are fastened to the rod 4 at 7 and passing through the hole 8 in the base 1 run through the pulleys 75 9 and 9' to the top king posts 10 of the elevators E. These wires are used for raising the elevators.

Control wires 11 and 11' are fastened to the back of the pilot's seat G at 7' and run 80 through the pulleys 12 and 12' to the bottom king posts 10' of the elevators E. These wires are used for lowering the elevators.

Control wires 14 and 14' are attached to 85 the sides of the pilot's seat G and run through pulleys 13 and 13' to the king posts 15 of the bottom ailerons D and D'. Wires 16 and 16' are for connecting the bottom ailerons D and D' with the top ailerons C 90 and C'. Wire 17 is a balance wire running, through pulleys 18 and 18' and connecting king posts 15' of the top ailerons. These wires are used to operate the ailerons.

The seat is provided with two sets of 95 safety belts 30 and 30' for securing the pilot around the thighs and chest and leaving his arms free, while his feet rest on the bottom of the fuselage within reach of the foot lever 20.

Control wires 19 and 19' are attached to the foot lever 20 and pass through pulleys 21 and 21' to the king posts 22 of the rudder F. These wires are for operating the rudder.

Having thus described the parts of the invention, we will now illustrate the operation of same.

In the operation of the invention two distinctive methods of control come into action, namely, the automatic factor and the human factor.

5 The automatic factor is obtained through the force of gravity holding the counter balance 5 straight downward, placing the rod 4 on which it is mounted, in a vertical position and holding the pilot's seat, to 10 which control wires are attached, level at all times, thus causing the flying machine to correct itself whenever it deviates from a horizontal attitude.

The human factor is used when it becomes necessary to change the flying attitude, such as banking and turning, ascending and descending. This is accomplished by various movements of the pilot's seat. The movements of the seat are actuated by 20 the movements of the pilot's body, while the rudder is operated by his feet.

The results of the different movements of the pilot's body would be as follows:

When the pilot leans backward, wires 6 25 and 6' are pulled and wires 11 and 11' recede, thus raising the elevators E and causing the flying machine to ascend.

When the pilot leans forward, wires 11 and 11' are pulled and wires 6 and 6' recede, 30 thus lowering the elevators E and causing the flying machine to descend.

When the pilot leans to the right, wire 14 is pulled and wire 14' recedes and since the top ailerons are connected by the balance wire 17 the movement depresses the left ailerons D' and C' and raises the right ailerons D and C, thus banking the flying machine up on its right side. In this operation when the flying machine is so placed 40 for turning, the pilot places his right foot on the right side of the foot lever 20 pulling the wire 19' and receding the wire 19, thus drawing the rudder F to the right and causing the flying machine to turn to the right.

45 Any opposite movement causes an opposite result.

The oil plunger 35 is used to counteract any tendency of the counter balance to oscillate. One or more of the oil plungers may 50 be used.

Having thus described the invention what we claim is new and desire to secure by Letters Patent, is:

1. A controlling mechanism for flying 55 machines of the character described, in combination with a base or support sustaining a pivot, the pivot, a rod running through

said pivot for supporting the pilot's seat, a counter balance mounted on lower end of said rod in such a way that it may revolve freely to decrease friction with the sides of the base or support, the tendency of said counter balance to hang straight downward actuating the controlling surfaces for the maintenance of stability and 65 holds the pilot's seat level.

2. A controlling mechanism for flying machines of the character described in combination with a support containing a pivot, the pivot, a counter balance secured to said pivot by means of a rod passing through said pivot, said rod also supporting the pilot's seat, wires secured to said rod and running through a hole in the base, thence to the top king posts of the elevators, said 70 wires for raising the elevators, wires attached to the back of the pilot's seat, thence to the bottom king posts of the elevators, said wires for lowering the elevators.

3. A controlling mechanism for flying 80 machines of the character described in combination with a base secured to the bottom of the fuselage a pivot supported by said base, a rod passing through said pivot, a seat for the pilot secured to said rod, a counter balance secured to the lower end of said rod to hold the seat level, wires attached to said seat for operating the stabilizing parts, an oil plunger secured to the pilot's seat and the frame of the flying 85 machine to counter act any tendency of the counter balance to oscillate.

4. A controlling mechanism for flying machines of the character described in combination with a base secured to the bottom of the fuselage, a pivot supported by said base, a rod secured to said pivot, a counter balance and a pilot seat secured to said rod, respectively, below and above the pivot, wires attached to the pilot's seat and to said rod for controlling the elevators and ailerons, a foot lever secured to the bottom of the fuselage in front of the said support, wires secured to said foot lever, and running through pulleys to the king posts of the rudder, said foot lever and wires for controlling the movements of the rudder, said 90 foot lever being operated by the pilot's feet.
